UNITED STATES PATENT OFFICE.

JOHAN M. ANDERSEN, OF BOSTON, MASSACHUSETTS, ASSIGNOR TO ALBERT AND J. M. ANDERSEN MANUFACTURING COMPANY, OF BOSTON, MASSACHUSETTS, A CORPORATION OF MAINE.

ELECTROMAGNETICALLY-OPERATED MECHANISM.

No. 872,400.

Specification of Letters Patent.

Patented Dec. 3, 1907.

Application filed January 20, 1906. Serial No. 296,953.

To all whom it may concern:

Be it known that I, JOHAN M. ANDERSEN, a citizen of the United States, residing in Boston, in the county of Suffolk and State of Massachusetts, have invented an Improvement in Electromagnetically-Operated Mechanism, of which the following description, in connection with the accompanying drawings, is a specification, like letters on the drawings representing like parts.

This invention relates to electromagnetically operated mechanism for effecting the operation of other devices, whereby said devices may be controlled from a station or point remote from the place or places where the devices are located.

The invention is especially adapted among other uses to be employed for operating substantially large electric switches.

20 The particular features of the invention will be pointed out in the claims at the end of this specification.

Figure 1 is a plan view of an operating mechanism embodying this invention. Fig. 25 2, a side elevation of the mechanism shown in Fig. 1. Fig. 3, a partial section and side elevation showing the apparatus in its operative position. Fig. 4, a detail to be referred to. Fig. 5, a longitudinal vertical section on the line 5—5, Fig. 1, and Fig. 6, an end elevation looking toward the left, Fig. 5.

In the apparatus herein shown as embodying this invention *a* represents a metal frame or casting, which is provided on its under side with two recesses or chambers *b*, *c*, preferably cylindrical in shape and containing electromagnets *d*, *e*, which have their spools mounted upon cores *f*, *g*, forming part of the casting *a*. The electromagnets *d*, *e*, have 40 operating with them disk-shaped armatures *h*, *i*, secured to rods or stems *j*, *k*, which are extended up through holes in the cores *f*, *g*. The magnet *d* may be made materially larger than the magnet *e*, and may be designated the lifting or working magnet, while the magnet *e* may be designated the release magnet. The working magnet *d* has its armature operatively connected with the device to be actuated, which device is not herein shown as it may be of various constructions, but for the purpose of this invention it may be supposed to be the movable member of a large electric switch. In the present instance, the armature *h* has its stem or rod *j*

connected with a lever *m*, comprising two 55 parallel parts or members located above the casting *a* and mounted on a pivot shaft or pin *n* on opposite sides of an upright *o* forming part of the casting *a*. The lever members *m* also straddle a second upright *p* arranged 60 in line with the upright *o*. The lever members *m* are tied together by the tie rods or bolts *q*, *r* and at their front end by a cross bar *s*, so that the two members *m* form one lever which is joined to the stem or rod *j* of the 65 armature, and this may be accomplished as herein shown by links 10 connecting lugs or projections 12 on the lever members *m* with a shaft or pin 13 extended through a hub or sleeve 14 formed on or attached to the armature stem or rod *j*. It will thus be seen that when the working magnet *d* is energized, its armature *h* is attracted, and the rod *j* is lifted, thereby through the links 10 turning 70 the lever *m* on its pivot *n* so as to elevate the rear end of said lever and lower the front end thereof. The elevating of the rear end of the lever *m* moves the device it is desired to operate, which device may be connected with the tie bolt *r* by a rod 16 or in any other 75 suitable manner.

It is desirable to be able to remove the current from the magnet *d* as soon as the lever is elevated as described, and for this purpose, a locking device is provided, which engages 85 the lever and retains it in its elevated or operative position until it is desired to again lower the lever and operate the device connected to it in the reverse direction or manner. To illustrate: Let it be supposed that 90 the device connected with the lever is an electric switch of large size requiring considerable power to operate it, and that when the lever *m* is elevated as above described, the switch is closed, and when said lever is lowered the switch is opened.

It will be seen that when the lever *m* is elevated, the main switch is closed and in order to retain the said switch in this position independently of the magnet *d*, the said 100 lever is engaged with a locking device, herein shown as a lever 20, pivoted at 21 to ears 22 on the casting, and provided at its upper end with a hook or latch 23, which is adapted to engage the upper side of the cross piece or 105 bar *s* of the lever *m*. The locking lever 20 is held in its engaging position by means of a spring 25.

Provision is made for disengaging the locking lever 20 from the lifting or operating lever, both electrically and by hand.

The release of the lever 20 may be effected electrically as herein shown by energizing the electromagnet *e*. The armature *g* of the electromagnet *e* has its stem or rod *k* extended above the top of the casting and carries the center pin 30 of toggle levers 31, 32, the lever 31 being pivoted to the upright *o* and the lever 32 being pivotally connected to the locking lever 20. It is preferred to employ two sets of toggle levers 31, 32 located on opposite sides of the stem or rod *k* and of the upright *o* and locking lever 20, the pin 33 connecting the front end of the levers 32 with the locking lever being extended through a slot 34 in said lever, which slot permits the locking lever to be moved independently of the toggle levers, by means of a handle 35, thereby enabling the locking lever to be manually operated to disengage it from the operating lever *m* and thus release the same when the toggle levers are in their straightened position.

When the electromagnet *e* is deenergized, the armature *i* is in its lowered position and the toggle levers 31, 32 are substantially straight and the locking lever 20 is at such time turned by the spring 25 into its operative position. When however the magnet *e* is energized, the armature *i* is attracted and the stem or rod *k* is elevated, thereby turning the levers 31, 32 on the pins 30 as a center and moving the levers 31, 32 into an inclined position (see Fig. 4), which causes the locking lever 20 to be moved backward out of engagement with the operating or lifting lever *m* and permits the latter to be turned or lowered by the weight attached to or connected with its rear end.

It will be noticed that when the armature *i* is in its lowered or unattracted position, which position may be termed its weakest position because when the magnet *e* is energized, the power of the armature for moving the lever 20 is the least, whereas the power of the toggle 31, 32 is the greatest because of its straightened position. As the armature *i* approaches the magnet *e*, its working strength is increased, and counteracts the diminishing power of the toggles, the power of which diminishes as the toggles are moved into their inclined position shown in Fig. 4.

Provision is made for cushioning the movement of the lifting lever *m* in opposite directions, and thus avoid injury to the actuating mechanism and to the parts or device operated by it. For this purpose a cylinder 40 is located above and in line with the stem or rod *j* of the lifting magnet *d*. The cylinder 40 may be made as herein shown and comprises two parts or halves 41, 42, the lower one of which may be cast integral with the uprights *o*, *p*, and the upper part or half of

which is secured to the lower part as by screws 43.

The cylinder 40 contains a piston 44 which is secured to the upper end of the rod or stem *j* and coöperates with two ports 45, 46 located intermediate the ends of the cylinder and communicating with a port or passage 47, which extends down through the wall of the cylinder and communicates with the atmosphere. The parts 41, 42 of the cylinder are provided with air admission valves 144, 145, which are automatically opened by the movement of the piston 44. The piston 44 on its up-movement draws air through the valve 145 into the cylinder 80 below the piston, and on its down-movement draws air through the valve 144 into cylinder above the piston. On the up-movement of the piston, the air above the piston is partially discharged through the port 85 45 and passage 47, and on the down-movement of said piston, the air is partially discharged through the port 46 and passage 47.

The ports 45, 46 are preferably located intermediate the ends of the cylinder, so that the piston 40 in its movement in opposite directions may cut off said ports and thereby form closed air chambers between the piston and the ends of the cylinder, which not only cushion the movement of the lifting lever but also prevent the piston from striking the ends of the cylinder with a severe blow. The lifting lever *m* may and preferably will constitute a circuit controller for electric circuits, and for this purpose, the said lever has secured to one side thereof a contact plate or member 50 electrically separated therefrom by suitable insulation 51, and has secured to its opposite sides a second contact member or plate 52 100 95 105 which is separated by suitable insulation 53.

The contact member or plate 50 coöperates with and is adapted to electrically connect two terminal brushes 54, 55, and the contact plate or member 52 coöperates 110 with and is adapted to connect two terminal brushes 56, 57.

The terminal brushes 54, 55 may and preferably will be arranged, so that they are engaged by the contact plate 50 when the lever *m* is in its lowered or non-operative position and are disengaged therefrom when the said lever is in its operative or elevated position.

The terminals 56, 57 are arranged so that they are disengaged by the contact plate 52 when the lever *m* is in its lowered or non-operative position, and are engaged thereby when the said lever is in its operative or elevated position.

The terminal brushes 54, 55 may be secured to metallic blocks 60, which are fastened to a base 61 of insulating material, which is secured to the casting *a*, and the brushes 56, 57 may be secured to a base 62 13

of insulating material which is fastened to the casting *a*.

The terminal brushes 54, 55 may be included in an electric circuit which is closed 5 at said terminals by the contact plate 50, when the lever *m* is in its non-operative position, and said circuit may be utilized for indicating at a distant point this position of the lever, or said circuit may be used for any 10 other desired purpose. The terminal brushes 56, 57 may be included in a separate circuit, which is closed at said terminals by the contact plate 52, when the lever *m* is in its operative position, and said circuit may be utilized 15 for indicating at a distant point this position of said lever, or said circuit may be used for any other desired purpose.

Provision is made for closing one of the electric circuits independently of the contact 20 plates carried by the lever *m*, and in the present instance, a manually operated switch 64 (see Fig. 1) is pivoted to lugs or ears 66 on the block 60 to which the brush 55 is connected, and is adapted to engage lugs 25 67 on the block 60 to which the brush 54 is connected.

One form of apparatus embodying this invention is herein shown, but it is not desired to limit the invention to the particular 30 construction shown.

Claims.

1. In an apparatus of the class described, in combination, a lever, an electromagnet having its armature connected to said lever 35 to turn the same into its operative position, a locking device coöperating with said lever to retain it in its operative position, toggle levers connected with said locking device, an electromagnet having its armature connected with said toggle levers to release the 40 said lever when said second electromagnet is energized, said locking device having provision for permitting it to be disengaged from said lever independently of said toggle levers and release magnet, substantially as described.

2. In an apparatus of the class described, in combination, a lever, an electromagnet having its armature connected to said lever 50 to turn the same into its operative position, a locking device coöperating with said lever to retain it in its operative position, toggle levers connected with said locking device, an electromagnet having its armature connected with said toggle levers to release the 55 said lever when said second electromagnet is energized, and circuit controllers movable with said lever, and circuit terminals with which said circuit controllers coöperate, substantially as described.

3. In an apparatus of the class described, in combination, a lever, an electromagnet having its armature connected to said lever, a locking device coöperating with said lever 60 and engaged thereby when said magnet is

energized, toggle levers connected to said locking device, a second electromagnet connected with said toggle levers to disengage said locking device from said lever when the said second electromagnet is energized, and 70 circuit controllers movable with said lever, substantially as described.

4. In an apparatus of the class described, in combination, a movable device, an electromagnet having its armature connected to 75 said movable device to effect movement thereof, a locking device coöperating with said movable device to lock it in the position into which it is moved when said electromagnet is energized, toggle levers connected with 80 said locking device, and a second electromagnet having its armature connected with said toggle levers to disengage said locking device from said movable device, when said second electromagnet is energized, substantially as 85 described.

5. In an apparatus of the class described, in combination, a movable device, an electromagnet having its armature connected to 90 said movable device to effect movement thereof, a locking device coöperating with said movable device to lock it in the position into which it is moved when said electromagnet is energized, toggle levers connected to 95 said locking device, a second electromagnet having its armature connected with said toggle levers to disengage the locking device from said movable device, when said second electromagnet is energized, said locking device having provision for being disengaged 100 from said movable device independently of said second electromagnet, and when said toggle levers are in their substantially straight position substantially as described.

6. In an apparatus of the class described, in combination, a casting having chambers on its under side, electromagnets located in said chambers, armatures for said electromagnets having stems or rods extended up through the said casting, uprights erected 110 upon said casting, a cylinder supported by said uprights, a piston in said cylinder having its piston rod connected with the rod or stem of one of said electromagnets, an operating lever pivoted to one of said uprights, 115 means for connecting said operating lever with the stem or rod of one of said electromagnets, a locking lever coöperating with said operating lever, toggle levers connected to said locking lever and to the rod or stem 120 of the second electromagnet, substantially as described.

7. In an apparatus of the class described, in combination, a casting having chambers on its under side, electromagnets located in 125 said chambers, armatures for said electromagnets having stems or rods extended up through the said casting, uprights erected upon said casting, a cylinder supported by said uprights, a piston in said cylinder having 130

its piston rod connected with the rod or stem of one of said electromagnets, an operating lever pivoted to one of said uprights, means for connecting said operating lever with the 5 stem or rod of one of said electromagnets, a locking lever coöperating with said operating lever, toggle levers connected to said locking lever and to the rod or stem of the second electromagnet, contact devices carried by 10 said operating lever, a circuit terminal coöperating with one of said contact devices in one position of said operating lever, and a second circuit terminal coöperating with the other of said contact devices in another position 15 of said operating lever, substantially as described.

8. The combination with an electromagnet and its armature, of toggle levers connected to said armature and arranged to occupy 20 a substantially straight position when said electromagnet is deenergized and to occupy a position inclined to each other when said electromagnet is energized, a device actuated by said toggle levers, and a pin and 25 slot connection between said device and one of said toggle levers to permit said device to be moved independently of the toggle levers when the latter are in their substantially straight position, for the purpose specified.

30 9. In an apparatus of the class described,

in combination, a movable device, an electromagnet to effect movement of said device into one position, means for locking said movable device in the position into which it is moved by said electromagnet, toggle levers 35 connected to said locking device, and a second electromagnet coöperating with said toggle levers to effect the release of the said movable device, substantially as described.

10. In an apparatus of the class described, 40 in combination, a movable device, an electromagnet to effect movement of said device into one position, means for locking said movable device in the position into which it is moved by said electromagnet, toggle levers 45 connected with said locking device a second electromagnet coöperating with said toggle levers to effect the release of the said movable device, and means coöperating with said movable device to cushion its movement 50 in opposite directions, substantially as described.

In testimony whereof, I have signed my name to this specification in the presence of two subscribing witnesses.

JOHAN M. ANDERSEN.
